UNITED STATES PATENT OFFICE

2,262,628

LIQUID DISPENSING DEVICE

Ronald M. Wilson, Philadelphia, Pa.

Application December 7, 1940, Serial No. 368,964

6 Claims. (Cl. 221—84)

My invention relates to improvement in liquid dispensing nozzles of the type generally used for dispensing motor fuel. Nozzles of this character are provided with nozzle-suspending means adapted for suspending the nozzle upon a bracket formed on a connection head which is secured on the upper end of a standard, or supply pipe, and to which head one end of a hose is attached, with the opposite end of the hose attached to a nozzle, whereby the nozzle may be readily suspended upon the bracket when not in use.

The object of my invention is to provide a nozzle with a strainer for straining the liquid as it is discharged from the nozzle, and provide novel means for mounting the strainer upon the nozzle.

A further object is to associate the strainer and the nozzle-suspending means in such a manner that the nozzle cannot be suspended upon the bracket unless the strainer is properly replaced upon the nozzle after it has been removed for cleaning purposes.

These together with various other novel features of construction and arrangement of the parts, which will be more fully hereinafter described and claimed, constitute my invention.

Referring to the accompanying drawing:

Fig. 1 is a longitudinal sectional view of my improved nozzle, showing devices in elevation and adapted for suspending the nozzle.

Fig. 2 is an enlarged sectional perspective view of the strainer and the sleeve upon which the strainer is secured, shown detached from the nozzle.

Fig. 3 is a perspective view of the smooth end of the nozzle after the sleeve and strainer have been removed.

Fig. 4 is a sectional perspective view showing a modified form of the nozzle-suspending means.

In the drawing in which like reference characters refer to like parts, Fig. 1 shows a dispensing device which includes a standard or supply pipe 6, secured in an erect position and connected with a source of liquid supply. A fitting in the form of a head 7 is connected with the pipe 6, a hose 8 is connected with the head, and a nozzle 10 is connected with the free end of the hose in the usual manner.

The head 7 is provided with a bracket 12 for suspending the free end of the nozzle upon the head 7, when the nozzle is not in use. Said bracket 12 is provided with a side opening 13, through which the flanged end of the nozzle 10 may be readily inserted and supported by lips 15 and 16, forming part of the bracket 12.

In carrying out my invention I employ a nozzle 10 having a smooth outer cylindrical surface at

its outlet end. An internal screw thread 18 is formed in the nozzle, as shown in Fig. 3.

A sleeve 20 is provided with an external screw thread 21 and is adapted to be engaged by the thread 18 of the nozzle. A cylindrical wire mesh screen, or strainer, 22 occupies the bore of the sleeve 20 and is secured to the sleeve by means of solder 23.

The strainer 22 fits loosely into the outlet end 10 of the nozzle 10 and extends into the latter a sufficient distance beyond the sleeve 20 to present a large filtering or straining surface. The inner end of the strainer 22 is pinched together and secured by solder 24.

The sleeve 20 is provided with a flange 25, or other suitable protuberance, which extends beyond the periphery of the nozzle, and forms bracket engaging means, adapted for suspending the nozzle from the bracket 12, as shown in Fig. 1.

The sleeve 20 and the flange 25 are preferably made in one piece, as shown in Figs. 1 and 2. The sleeve and flange may be formed separately, as shown in Fig. 4, wherein the sleeve 28 is provided with an enlarged head 29, adapted for engaging a flange, or washer, 30, and securing the same upon the end of the nozzle. The flange, or washer, 30 projects beyond the diameter of the nozzle and forms the bracket engaging means by which the nozzle may be suspended upon the bracket 12, when the sleeve and strainer are secured upon the nozzle.

The novel means for mounting the strainer upon the nozzle insures the replacement of the strainer upon the nozzle after the strainer has been removed for cleaning the same. By combining the sleeve and strainer as a removable unit, and arranging the sleeve for controlling the position of the flange 25, or the flange 30, relatively to the nozzle, the nozzle cannot be suspended upon the bracket 12 until the sleeve and strainer are properly attached to the nozzle.

Should the attendant neglect to attach the sleeve, carrying the strainer 22, to the nozzle it will be impossible for him to suspend the nozzle upon the bracket 12, due to the smooth surface of the nozzle at its discharge end.

My invention insures the nozzle always being provided with a fuel strainer properly installed in the nozzle.

Various changes in the construction and arrangement of the parts may be made without departing from my invention.

I claim:

1. In a liquid dispensing nozzle, a sleeve, means detachably mounting the sleeve upon the dis-

charge end of the nozzle, a strainer secured upon the sleeve, and nozzle supporting means retained upon the nozzle by the sleeve and arranged to be detached from the nozzle by the removal of the sleeve from the nozzle.

2. In a liquid dispensing nozzle, a sleeve, means detachably mounting the sleeve upon the discharge end of the nozzle, a strainer mounted upon the sleeve and held in liquid straining position within the nozzle by the sleeve when the latter is secured upon the nozzle, and projecting means associated with the sleeve and extending in a lateral direction beyond the nozzle by which the latter may be held in a suspended position when the sleeve and strainer are mounted upon the nozzle.

3. In a liquid dispensing nozzle, a sleeve, means detachably mounting the sleeve upon the discharge end of the nozzle, a strainer secured upon the sleeve and held in liquid straining position within the nozzle by the sleeve when the latter is secured upon the nozzle, a flange secured upon the sleeve and projecting beyond the diameter of the nozzle and adapted for mounting the nozzle in a suspended position.

4. In a liquid dispensing nozzle, a sleeve, means detachably mounting the sleeve upon the dis-

charge end of the nozzle, a strainer positioned within the nozzle and retained therein by the sleeve, said nozzle having a uniform diameter adjacent to the end thereof, a collar detachably held upon the nozzle by the sleeve when the latter is secured upon the nozzle, and said collar having a greater diameter than the nozzle whereby the latter may be suspended by said collar.

5. A liquid dispensing device including a bracket mounted in a fixed position, a nozzle, a sleeve, means detachably securing the sleeve upon the outlet end of the nozzle, a strainer removably secured within the nozzle by the sleeve, and means associated with the sleeve and adapted for engagement with said bracket for suspending the nozzle upon the latter.

10 6. A liquid dispensing device including a fuel outlet connection head, a hose connected with said head, a nozzle upon the opposite end of the hose relatively to said head, a nozzle suspending bracket associated with said head, a sleeve, means detachably securing the sleeve upon the outlet end of the nozzle, a strainer occupying the nozzle and retained by said sleeve, and bracket engaging means associated with the sleeve adapted for suspending the nozzle upon said bracket.

RONALD M. WILSON.
